UNITED STATES PATENT OFFICE.

CHALKLEY T. FOWLER, OF CHILlicothe, OHIO.

DESIGN FOR A HAT AND COAT RACK.

SPECIFICATION forming part of Design No. 19,432, dated November 19, 1889.

Application filed August 27, 1889. Serial No. 322,158. Term of patent 3½ years.

To all whom it may concern:

Be it known that I, CHALKLEY T. FOWLER, a citizen of the United States, residing at Chillicothe, in the county of Ross and State 5 of Ohio, have invented and produced a new and original Design for a Hat and Coat Rack, of which the following is a specification.

The design is shown in the accompanying drawings, Figure 1 being a front elevation, 10 and Figs. 2, 3, 4, and 5 sectional views.

The design illustrated shows a hat and coat rack rectangular in outline, having an upwardly-projecting central portion provided with crescent-shaped coat-holders at the base 15 and hat-shaped holders at the top. The cen-

ter is provided with the usual mirror, flanked on the right and left by a series of horn-shaped horizontal holders or supports, as shown in the drawings.

In practice I may extend the vertical standards or supports sufficiently to reach the floor; but this would not change the general or leading characteristics of the design as shown.

What I claim is—

The design for a hat and coat rack, as here- 25 in shown and described.

CHALKLEY T. FOWLER.
